UNITED STATES PATENT OFFICE.

HENRY BAKER, OF KANSAS CITY, MISSOURI.

DESIGN FOR A SHAWL.

45,979.

Specification for Design.

Patented June 23, 1914.

Application filed March 18, 1914. Serial No. 825,699. Term of patent 7 years.

To all whom it may concern:

Be it known that I, HENRY BAKER, a citizen of the United States, residing at Kansas City, in the county of Jackson and State of Missouri, have invented a new, original, and ornamental Design for Shawls, of which the following is a specification, reference being had to the accompanying drawing, forming part thereof.

The figure is a plan view of a portion of a shawl illustrating my new design.

I claim:

The ornamental design for a shawl, as shown.

In testimony whereof I affix my signature in presence of two witnesses.

HENRY BAKER.

Witnesses:

WILLIAM D. FRICKE,
JAMES R. BREAKFIELD.
